JOHN W. WILCOX, OF NEW YORK, N. Y.

Letters Patent No. 67,092, dated July 23, 1867.

DOCUMENT-ENVELOPE.

The Schedule referred to in these Letters Patent and making part of the same.

TO ALL WHOM IT MAY CONCERN:

Be it known that I, JOHN W. WILCOX, of the city, county, and State of New York, have invented a new and useful Improvement in Envelopes; and I do hereby declare that the following is a full, clear, and exact description thereof, which will enable others skilled in the art to make and use the same, reference being had to the accompanying drawings, forming part of this specification, in which—

Figure 1 is a plan view of the paper as cut and creased for folding and forming my improved box-envelope. Figure 2 is a top view of the envelope when finished.

Figure 3 is a longitudinal section of my improved box-envelope taken in the line $x\ x$, fig. 2.

Figure 4 is a transverse section of the same taken in the line $y\ y$, fig. 2.

Similar letters of reference indicate like parts.

This invention relates to an improved mode of forming box or document-envelopes, and consists in so cutting the paper or other material of which they are made as to involve the least possible waste, and in creasing and folding the ends of the envelopes together in such manner that they are fortified and stiffened by a double thickness of the material throughout and a treble thickness at the corners, whereby the box-envelope is formed wholly of one sheet, and is very materially improved in construction, and made stronger than by any known method of arrangement.

For cutting the form or pattern of the envelope and creasing it for folding, as represented in fig. 1, I employ the usual tools and processes of the trade, and cut the paper or other material in the geometrical proportions required to make the ordinary rectangular envelope for containing documents, commonly called box-envelopes, which are in the form of a parallelopiped.

In fig. 1, A is the back of the envelope, B the top, and C the flap. The dotted lines $a\ a$ in the drawing indicate the creases in which the folds of the envelopes are made to give it the proper form for construction and use. On the ends of the envelope creases are made at proper distance from the outer edges and parallel to them, and in line with the cut at the ends of the flap C. These creases extend across the pattern of the envelope, to make flaps for turning up and forming the ends of the box-envelope, $b\ b$ being the flaps thus provided on the back A, and $c\ c$ the flaps on the top B. Between the flaps $b\ b$ and $c\ c$, at each end of the envelope, are small flaps or tongues $d\ d$, and on the opposite ends of the flaps $b\ b$ are similar small flaps or tongues $e\ e$, which flaps are all made by cutting away narrow strips of the material, or by division cuts running from the edge of the pattern to the creases for folding.

When the pattern has been cut and creased in this manner, the box-envelope is formed by folding the top B over the back A in the usual way, and in such manner that the end flaps $b\ b$ and $c\ c$ shall lie against and in each other at their respective ends, and be pasted or gummed together, as shown by fig. 3. By this arrangement of the parts, the ends of the box-envelope are made of double thickness of the material throughout, to give strength precisely where it is most needed, and furnish substantial transverse supports for the envelope. The small flaps or tongues $e\ e$ and $d\ d$ are also folded in and pasted down upon the ends, either between the flaps $b\ b$ and $c\ c$ or on the inside, as desired, and as shown in fig. 4. This arrangement of the small flaps, so far as they extend, makes a treble thickness of the ends, and, being in the corners of the envelope, affords great additional strength at points which require fortifying. A further improvement in the construction of envelopes is doubling and pasting two angular flaps $f\ f$ within the top B, which are formed by making one division cut running a short distance from the edge, and creasing from its terminus to the edge at any desired angle, as shown by fig. 1. These flaps add strength to the middle of the envelope, where the ends of documents are introduced and the tie of the flap binds, which is a point of importance and value. The flap C is turned over, and secured in the ordinary way when used.

Having thus described my invention, what I claim as new, and desire to secure by Letters Patent, is—

Constructing a box or document-envelope, with double ends throughout and treble ends in part, by folding and uniting flaps cut out of one sheet of paper or other material, substantially as herein described.

The above specification of my invention signed by me this 5th day of October, 1866.

JOHN W. WILCOX,

Witnesses:

WM. F. McNAMARA,
ALEX. F. ROBERTS.
